APPARATUS FOR GENERATING STEAM

Otto Engler, Cassel-Wilhelmshöhe, Germany, assignor to Schmidt'sche Heissdampf-Gesellschaft m. b. H., Cassel-Wilhelmshöhe, Germany

Application June 25, 1935, Serial No. 28,366
In Germany June 28, 1934

9 Claims. (Cl. 122—33)

The invention relates to a method and apparatus for generating steam, and particularly for the indirect generation of steam through a flowing heating medium.

5 In the past, in the indirect generation of steam by means of a fluid heating medium such as superheated steam, it has been usual to heat the heating medium at one point and then to pass it at a different point in heat exchange relation with the water to be vaporized. In other words, the absorption of heat by any part of the heating medium and the radiation of heat thereby (that is, the giving up of heat to the water to be vaporized), have taken place at different times and at different points. This alternate absorption and radiation of heat must be carried on repeatedly in order to obtain proper efficiency in the generation of steam.

The fundamental difference between the 20 method according to the present invention, and such earlier procedures, is that in the new process the radiation of heat to the liquid to be vaporized is combined with the supply of heat to the heating medium, so that the two steps are simultaneous. 25 The new method of indirect steam generation by the use of a flowing heating medium consists, preferably, in supplying heat to the heating medium from an exterior source during the same period in which it is giving up heat to the liquid 30 to be vaporized.

The invention is preferably carried out by means of a system of double walled tubes which are heated by fire or combustion gases, and which provide separate paths of flow for the liquid to 35 be vaporized and the heating medium to move in heat exchange relation with each other. For example, the liquid to be vaporized may flow through the inner space of the tubes and the heating medium through the annular outer space. 40 The inner tube may be in the nature of a Field tube.

The principal advantage of the present invention lies in the fact that the average temperature difference between the heating medium and 45 the liquid to be vaporized is greater, assuming the same maximum temperature for the heating medium, than in prior steam generating methods, in which the temperature of the heating medium drops rapidly during the time in which it is giving up heat to the liquid to be vaporized. As a 50 result, with the same dimensions of heat exchange surfaces and without submitting the heat absorption surfaces for the heating medium to any higher temperatures, a greater boiler output 55 may be obtained.

The invention further contemplates an arrangement in which the greater part of the heat required for the heating and vaporization of the liquid to be vaporized, and preferably substantially all of this heat, is supplied to the heating 5 medium when it is in heat exchange relation to the liquid. The invention is particularly applicable to arrangements in which the steam thus indirectly generated is itself used as the heating medium for vaporizing further quantities 10 of the liquid, and is then led off to its point of consumption.

Further objects and advantages of the present invention will be more fully apparent from the following description, particularly when taken in 15 conjunction with the accompanying drawings which form a part thereof.

In the drawings:

Fig. 1 is a vertical section, partly diagrammatic, through a steam generator embodying my 20 invention.

Fig. 1a is a similar view showing a modification of the heating arrangement of Fig. 1.

Fig. 2 is an enlarged cross section through the steam generating portion of the arrangement 25 shown in Fig. 1.

Fig. 3 is an enlarged cross section substantially on the line III—III of Fig. 2.

Fig. 4 is a cross section on the line IV—IV of Fig. 3.

Fig. 5 is a cross section similar to a portion of Fig. 2 through a modified form of tube construction.

Fig. 6 is a cross section substantially on the line VI—VI of Fig. 5.

Fig. 7 is a vertical section, partly diagrammatic, through a modified form of generator.

Figs. 8 and 9 are detailed views, principally in section, of portions of the device shown in Fig. 7.

Fig. 10 is a cross section, partly diagrammatic, through a modified form of the invention particularly adapted for marine boilers.

Fig. 11 is a cross section through a part of the vaporizing system of the device shown in Fig. 10.

Fig. 12 shows in cross section, partly diagrammatic, a portion of a modified form of marine boiler.

Fig. 13 is a section through a part of the vaporizer tubes of Fig. 12.

Fig. 14 shows, in section, a further modification of the fluid circuit portion of a further type of generator.

As shown in Fig. 1, the construction includes an upper steam drum 1 which is adapted to hold 55

water to be vaporized and to receive steam generated by the device. The loop or U tubes 2, the construction of which will be described in detail below, are arranged to extend transversely across a vertical heating flue 4 which is located above the combustion chamber or fire box 3 of a suitable furnace. The upper end of the flue 4 is connected with a second vertical heating flue 5. Arranged in the flue 5, from top to bottom, are a superheater 6, a feed water preheater 7 and an air heater 8. These devices are merely indicated diagrammatically in the drawings.

The loop tubes 2 consist of casings into which inner tubes, preferably constructed as Field tubes, may extend. These tubes consist, for instance, of inner members or tube sections 9 and outer members or tube sections 10 (Figs. 2 to 4), forming therebetween an annular space 29. The Field tubes extend down into the legs of the U or loop tubes, and the closed ends of the tube sections 10 are located near the ends of the legs of the loop tubes. The bent portions or elbows 12 of the U tubes, which have no inner tubes passing therethrough, are reduced in cross section so that the clear cross section within the bends is substantially the same as the cross section of the annular space 13 outside the outer Field tube sections 10.

The Field tubes are arranged in a plurality of vertical series. The ends of the Field tubes of each series are arranged in one of a set of vertical tubular casings 14, which are divided by intermediate walls 15 into water chambers 16 and steam chambers 17. The inner sections 9 of the Field tubes communicate with the water chambers 16, and the outer sections 10 with the steam chambers 17. At their upper ends the water chambers 16 of the cylinders 14 are connected by nipples 18 with the water space of drum 1, and at the lower ends by nipples 19 with a water cylinder or header 20. Ascending pipes 21 extend from the upper ends of steam chambers 17 of casings 14 to the drum 1.

The outer sections 10 of the Field tubes are suitably secured in the wall of casing 14. The inner sections 9, on the other hand, are removably secured by means of a special arrangement to be described. Adjacent the end of the tube section 9 which is arranged within the casing 14 is a washer 22, secured to the tube section, and which fits into and closes an opening in the intermediate wall 15. This washer may be flanged so as to close tightly the opening in the wall. At the end, the tube section 9 carries a closure cover 23 which fits into an opening 24 in the wall of casing 14. Tube 9 may be inserted from the exterior through the casing 14 into the tube section 10, since the opening 24 is made large enough to permit the washer 22 to pass through. The cover 23 may be held tightly in place by means of a pressure yoke 25 which engages the cover 23 and is held in place by bolts and nuts 26. The cover 23 may be also provided with a flange which fits in a recess or seat in the casing 14, so that a suitable packing member 27 arranged therebetween will produce a tight joint at this point.

The inner tube section 9 is cut away between the front wall of casing 14 and the intermediate wall 15, so as to provide openings 28 through which the water in chamber 16 may pass into the interior of the inner tube sections 9. The water then flows through these sections 9 and back through the spaces 29 within the sections 10 to the steam chamber 17. Within the spaces

29 the water is heated by steam flowing in the tubes 2, and is thus converted into steam.

The tubes 2 are sealed at their ends by the provision of rings or washers 30, the ends of the tubes being bent down around these washers and welded to the tube sections 10.

The heating steam or heating medium is taken from drum 1 and passes through pipe 31 to a lower header 32, from which it passes through pipes 33 to the lowest tubes of each of the vertical rows of tubes 2. The tubes of each vertical row are connected together in series by suitable pipes 34, so that the heating medium passes through the various tubes successively. From the upper loop tube 2 of each series, pipes 35 extend to a steam collecting chamber 36, which is separated from the remaining space in the drum 1 by a shield or shell 37. Pipes 39 extend from the steam collecting chamber 36 to the superheater 6 and from this the steam is led off to a point of consumption. These pipes are preferably arranged along the top wall 38 of the heating flues 4.

The water being supplied to the drum 1 for the further generation of steam may be preheated by passing it through the feed water preheater 7 and then through pipe 40 to the drum 1.

The heating steam or heating medium flowing in the spaces 13 of the U tubes is thus supplied with heat continuously by the flue or combustion gases passing up from combustion chamber 3. At the same time, the heating medium is continuously giving off heat to the water flowing through the Field tubes and thus generating steam which flows through the pipe 21 to the drum 1.

The heat is thus transmitted by the heating medium to the water to be vaporized, at any predetermined maximum temperature of the heating medium, with a continuous high difference of temperature. In other words, the temperature of the heating medium does not drop as it gives up its heat and thus approach the heat of the liquid to be vaporized, which would reduce the radiation efficiency considerably for the same radiation space; but instead the heating medium is kept at a high temperature during the whole period in which it is giving off heat to the liquid to be vaporized. Therefore the heat exchange surfaces required for a given output of steam may be made smaller where the present invention is used.

The ratio of the heat absorbed through the tubes 2 by the heating medium to the heat given off by the heating medium to the liquid to be vaporized may be modified and suitably predetermined by varying the dimensions of the heating surfaces. For instance, the heat absorbing surface of the outer Field tube sections 10 may be increased by the provision of ribs, so that the heat absorbed by the heating medium will be transferred more rapidly to the liquid to be vaporized. In this manner, the temperature of the heating medium may be prevented from exceeding a predetermined temperature, and the temperature of the tubes 2 which are subjected to the heat of the flue gases may be kept relatively low. Fig. 4 shows in cross section an arrangement of ribs 41 on the outer section 10 of the Field tube. These ribs may be staggered as feet for supporting the Field tube sections 10 within the tubes 2 to produce an irregular path for the heating medium so that it passes through the chamber 13 in eddies, which will further im-

prove the transmission of heat to the liquid to be vaporized.

The arrangement may be modified in various fashions, in that it is not necessary to utilize all the steam generated in the drum 1 as heating medium for the generation of further steam. In order to start the generator, steam may be supplied from an exterior source until steam is being generated at a sufficient rate to provide the necessary heating medium for continuous operation. However, it is also possible to force the circulation of water through the tubes and, if necessary, through the superheater until sufficient steam is generated to permit the operation to be continued. Steam from an external source may also be provided as the heating medium if desired.

In the embodiment shown, the saturated steam which is being used as a heating medium passes first to the lower or most highly heated of the tubes 2. This has the advantage that the steam flowing through the annular space of the lower tubes is comparatively cool, and thereby serves to cool these tubes to a certain extent and protect them from the heat of the combustion gases. The arrangement, however, may be reversed where the tubes are subjected to relatively low temperatures only, in which event it is preferable to cause the heating medium and the flue gases to move in counter-current relation, so that the heating medium will leave the tubes at a point of comparatively high temperature, from which it passes to its point of use as shown in Fig. 1a.

A modified form of tube structure is shown in Figs. 5 and 6. In this arrangement, instead of providing separate tubes 34 connecting the loop tubes to each other, these loop tubes are connected through the same casing which provides the water and the steam chambers. Vertical casing 14 here contains an intermediate wall 15 separating water space 16 from steam space 17, and a further separating wall 42 which separates steam space 17 from a heating steam chamber 43. The ends of the tubes 2 are suitably secured in the wall of casing 14 in communication with chamber 43. Horizontal walls 44 arranged in the chamber 43 divide the same into a plurality of spaces. These walls are arranged between the legs of each loop tube, so that the steam may flow from one tube to the next but is then forced to flow through the tube to reach the next upper space. The heating medium thus is forced to flow successively through the tubes 2. The upper end of the chamber 43 may be connected in any suitable manner to the space 36 within the drum 1.

In this arrangement, the outer Field tube sections 10 are also provided with flanged washers 45 secured on their ends which fit in openings in the separating wall 42. The inner tubes 9 carry at their ends plugs or closure members 23 which fit in openings in the wall of casing 14, and are held in place by pressure yokes 46 and nuts 47. The ends of outer tube sections 10 are cut away, so as to form legs 48 which rest against the washers 22 fixed on tube sections 9, the spaces between the legs 48 providing for the escape of steam from the tube sections 10 into the space 17.

A further modification of the invention is shown in Fig. 7. This arrangement in general is the same as that shown in Figs. 1 to 4. However, double walled tubes 50 are provided which extend across the flue space 4 and down the rear wall thereof below the loop tubes 2. These tubes 50 form a rear wall for the combustion chamber

3. The tubes 50 enclose inner tubes 51, which fit within the tubes 50 and are bent jointly with the outer tubes. Inner tubes 51 are connected to the steam chambers 17 of the casings 14 (Fig. 9) to which the outer tube sections 10 of the Field tubes in the loop tubes 2 are also connected. The upper ends of outer tubes 50 are sealed off in the same manner as the ends of loop tubes 2, and connecting pipes 52 extend from outer tubes 50 to the lowest of each series of loop tubes 2. 10

At the lower ends, the outer tubes 50 and inner tubes 51 are connected with a cylinder 53, which is subdivided by a separating wall 54 into a steam chamber and a water chamber. Outer tubes 50 are suitably secured in the wall of cylinder 53 15 and communicate with the steam chamber section thereof. Inner tubes 51 engage at their lower ends with tube sections 55. Flanged washers 56 secured on tube sections 55 fit into and close openings in separating wall 54. Sections 20 55 also carry plugs or closures 57 which are suitably secured in openings in cylinder 53 by yokes 59 and nuts 60. Rings or collars 58 fit into the aligned ends of tubes 51 and tube sections 55 and thus form tight connections therebetween. The 25 parts of the tube sections 55 within the water chamber are cut away as at 63 to provide openings through which the tubes 51 may communicate with the water chamber.

A pipe 61 connects the water space of the 30 chamber 53 with the drum 1, while a pipe 62 connects the steam space of cylinder 53 with the top of the drum 1 so as to receive steam therefrom. The heating medium or heating steam flows through the outer spaces of the tubes 50 35 and then through the spaces of tubes 2 to the steam collecting chamber 36. The water to be vaporized passes first through pipe 61 to the water space of chamber 53, then through inner tubes 51 and then through chambers 17 to the 40 drum 1.

Figs. 10 and 11 show a marine boiler having in the usual form two groups or sets of inclined tubes 66 with a combustion chamber 64 arranged therebetween. These groups of tubes communicate with a common steam drum 65. However, according to the invention, such tubes are not simple tubes, but consist of outer tubes 66 and inner Field tubes consisting of outer tube sections 68 and inner tube sections 69. The outer tubes 66 of each set form in effect a continuous tube. The straight sections of the outer tubes are connected at their lower ends by closed loops or bights, and at their upper ends adjacent the drum 65 by closures or covers 67. The Field tubes extend through the covers 67 into the straight sections of the outer tubes. The outer Field tube sections 68 are suitably secured in the wall of the drum 65, and the inner tube sections 69 also communicate with the interior of 60 the drum. From the drum 65 the water flows downwardly in the inner tube sections 69, and the mixture of steam and water formed by the heating rises through the outer tube sections 68 into the cylinder 65. 65

The outer tube groups each consists of a plurality of tubes connected at one end with a lower steam cylinder 71 and at the other end with a steam cylinder 72. Heating steam drawn from the top of drum 65 passes downwardly through 70 pipe 73 into drums 71. It then passes successively through the outer tubes 66 to drum 72, from which it passes through pipe 74 to a superheater 75 and thence to its place of use. It is evident that in this form also the heating steam 75

is receiving heat from the fire box 64 at the same time that it is giving up heat to the water to be vaporized in the Field tubes.

In the arrangement shown in Figs. 12 and 13, which is in many respects similar to that of Figs. 10 and 11, the outer tubes 66 instead of being connected at their lower ends by loops or bights are connected by closures or plugs 76. Moreover, in this form Field tubes are not used, but instead simple water tubes 77. These tubes are arranged tightly in the plugs 67 and 76. Tubes 77 are connected at their upper ends to a drum 65, and at their lower ends to a drum 78. Two steam chambers 79 and 80 are formed by suitable separating walls which divide them from the water space of drum 78. One end of the outer tube group 66 is connected by a pipe 81 with steam chamber 79, and the other end by a pipe 82 with steam chamber 80. A pipe 73 connects drum 65 with steam chamber 79. A further pipe 83 connects the water space of drum 65 with the water space of drum 78. From the space 80 the steam flows through pipe 74 and superheater 75 to the point of consumption.

25 A further modified form of the invention is shown in Fig. 14. In this construction, the heating steam after passing through the tubes 2 is not led away to a point of consumption but is returned in a closed circuit through the heating tubes. Furthermore, this steam is not taken from the drum 1 of the indirectly heated generator, but is drawn from a separate source. In the arrangement shown in this figure, the drum 1 and the Field tube arrangement is the same 30 as that shown in Figs. 1 and 2, the loop tubes 2 also corresponding to those shown in the earlier figure. However, the heating steam is supplied through a passage 100 into a steam cylinder 101 from any suitable source. The steam 35 flows through a passage 102 to a pump 103 which forces it through passage 104 to header or distributing cylinder 105. Pipes 106 extend from header 105 to the lower tubes 2 of each vertical group. The heating steam passes 40 through the loop tubes 2 and then is returned through tubes 107 to cylinder 101. In this form 45 also, as will be noticed, the heating steam merely serves as a heating medium, and substantially all the heat actually supplied for generating steam is received from the flue gases, the heating steam being merely an intermediary for such heat.

50 While the flow of water to be vaporized in the construction disclosed takes place through gravity and through the generation of steam, it is obvious that such flow could be caused in any other suitable manner, as for instance by the provision of a water circulating pump between the steam drum and the openings of the inner Field tube sections.

55 While I have described herein several embodiments of my invention, I wish it to be understood that I do not intend to limit myself except within the scope of the appended claims.

60 I claim:

1. A steam generator, comprising a steam drum, a plurality of Field tubes having inner and outer tube sections, means for conducting liquid from said drum to the inner tube sections, means for conducting steam from the outer tube sections to the drum, a plurality of other tubes surrounding said Field tubes, means to conduct steam from said drum to said second tubes and from said second tubes to a point of use, and means to heat said second tubes.

2. A steam generator comprising a steam drum, a plurality of Field tubes having inner and outer tube sections, means for conducting liquid from said drum to the inner tube sections, means for conducting steam from the outer tube sections to the drum, a plurality of second tubes surrounding said Field tubes, said second tubes being connected in series, means to conduct steam from said drum to said second tubes and from said second tubes to a point of use, said last conducting means from the drum being connected to that one of said second tubes which is exposed to the highest temperature, and means to heat said second tubes.

3. A steam generator comprising a steam drum, a plurality of double-walled tubes, means to conduct liquid from said drum to the inner spaces of the tubes, means for passing off the steam generated in said inner spaces, means to conduct steam from said drum to the outer spaces of said tubes, said outer spaces of said tubes being connected in series, and said last conducting means being connected to the outer space of that tube which is exposed to the highest temperature, and means to heat said tubes.

4. A steam generator comprising a steam drum, a plurality of Field tubes having inner and outer tube sections, means for conducting liquid from said drum to the inner tube sections, means for conducting steam from the outer tube sections to the drum, a plurality of second tubes surrounding said Field tubes, said second tubes being connected in series, means to conduct steam from said drum to said second tubes and from said second tubes to a point of use, and means to heat said second tubes.

5. A steam generator comprising a steam drum, a plurality of Field tubes having inner and outer tube sections, means for conducting liquid from said drum to the inner tube sections, means for conducting steam from the outer tube sections to the drum, a plurality of second tubes surrounding said Field tubes, means to conduct steam from said drum to said second tubes and from said second tubes to a point of use, said last conducting means from the drum being connected to that one of said second tubes which is exposed to the highest temperature, and means to heat said second tubes.

6. An apparatus for the indirect generation of steam comprising a combustion chamber and steam generating means, said means consisting of a system having a steam drum, a plurality of steam generating double-walled tubes located substantially entirely within said combustion chamber and forming substantially the whole of the vaporizing means, means to conduct liquid from said drum to the inner spaces of the tubes, means to conduct steam to the outer spaces of said tubes, whereby said liquid is converted into steam, means to conduct said liquid converted into steam to said drum, and means to heat said tubes.

7. An apparatus as in claim 6, said double-walled tubes comprising an inner Field tube surrounded by a second tube.

8. A steam generator for the indirect generation of steam comprising a combustion chamber and a steam generating system, said system consisting entirely of a steam drum, a plurality of double-walled tubes located substantially entirely within said combustion chamber and forming substantially the whole of the steam generating means, means to conduct liquid from said drum to the inner spaces of said tubes, means to

conduct steam generated in said inner spaces to said drum, means to conduct steam to the outer spaces of said tubes, and means to heat the outside of the tubes.

5. 9. A steam generator for the indirect generation of steam consisting of a steam drum, a plurality of double-walled tubes forming substan-

tially the whole of the steam generating means, means to conduct water to the inner spaces of said tubes, means to conduct steam generated in the inner spaces to said drum, means to conduct steam to the outer spaces of said tubes, and 5 means to heat said tubes.

OTTO ENGLER.
